UNITED STATES PATENT OFFICE

STELLA A. TREJO, OF KANSAS CITY, MISSOURI, ASSIGNOR OF FIFTY-FIVE PER CENT
TO WILLIAM B. LESLIE, OF KANSAS CITY, MISSOURI

NEEDLE

Application filed September 26, 1929, Serial No. 395,306. Renewed August 8, 1932.

This invention relates to improvements in needles and it consists of the constructions, combinations and arrangements herein described and claimed.

5 An object of the invention is to provide a needle primarily intended for use in sewing machines but possessing characteristics which are conceivably capable of being embodied in needles of other types.

10 Another object of the invention, and one bearing directly on the preceding statement, is to provide a needle capable of being threaded instantly, the construction being such that chafing of the thread in the eye and consequent breakage thereof when the needle is 15 in use is obviated.

A further object of the invention is to provide a needle of the so-called self-threading kind in which the spring arm, which is 20 one of the outstanding characteristics, is prevented from unrestricted outward movement, hence the likelihood of snapping off while the needle is in use, by the provision of a lug or hump that has engagement in a 25 recess in the body of the needle.

Other objects and advantages will appear in the following specification, reference being had to the accompanying drawing, in which:—

30 Figure 1 is a front elevation on an enlarged scale of the improved needle.

Fig. 2 is a side elevation on a still further enlarged scale, particularly illustrating the several outstanding improvements.

Fig. 3 is a cross-section taken on the line 3—3 of Fig. 2.

Fig. 4 is a cross-section taken on the line 4—4 of Fig. 2.

40 Fig. 5 is a cross-section taken on the line 5—5 of Fig. 2.

Fig. 6 is a cross-section taken on the line 6—6 of Fig. 2.

45 Fig. 7 is a cross-section taken on the line 7—7 of Fig. 2.

Fig. 8 is a longitudinal section taken on the line 8—8 of Fig. 2.

As previously indicated, the needle herein disclosed is of the so-called self-threading type in the use of which it is merely necessary to hold a portion of the thread under tension and direct it to the needle eye, thus avoiding the laborious and nerve-straining operation of thrusting the pointed end of a thread directly through the eye. In the foregoing respect, the present needle is an improvement 50 on the needle disclosed in an application filed by Stella A. Trejo, May 2, 1929, Serial No. 359,949.

Attention is directed to the drawing. The 60 shank 10 and head 11 are parts of a sewing machine needle of more or less conventional style. The needle is pointed at 12 and has an eye 13 into which it is proposed to introduce the thread 14 without the necessity of pointing the thread and thrusting it through 65 according to a familiar performance.

As will be observed by comparing the series 70 of cross-sectional views in Figs. 3 to 7, inclusive, the needle shank is cylindrical for the major portion of its length but gradually flattens to an oval shape as the fabric penetrating point 12 is approached. A portion 75 15 of one edge of the needle shank is made plane or level in the direction of the minor axis, and it is against this plane portion that the correspondingly plane surface of a spring arm 16 bears. The upper terminal of this spring arm is either rounded at 17 or otherwise so formed that a thread when properly held under tension is readily slipped 80 therebehind preparatory to pressing or forcing it downwardly through a part of a channel that the confronting surfaces 15 and 16 afford.

85 A portion of the body of the shank 10 is rounded at 18 to produce what might be known as a heel. It is at a region 19 adjoining this heel that the spring arm 16 has its origin. In other words, the region 19 is the 90

base of the spring arm. The base 19 merges with and forms part of a horn 20 that extends in the direction of the longitudinal center of the needle and terminates in a point 21 at one side of the eye 13. This point fits between and is largely concealed by a pair of lips 22 which comprise a part of the needle and in the manufacture of the latter are simply pressed inwardly far enough to partly encompass the point 21, as plainly shown in Figs. 2, 7 and 8. From the latter it will be observed that the passage of thread out of the thread channel will not be restricted by either the point 21 or the lips 22. The primary purpose of the lips is to guard the point 21. It would be undesirable to have the point 21 project into the eye 13 even to the slightest extent because then there would be the likelihood of the point catching the thread with the perpetual possibility of breaking it during the course of sewing. But by employing the lips 22, the thread will be caused to ride over and pass the point with no likelihood whatever of chafing it.

25 A lug or hump 23 formed on the horn 20 is engageable in a recess 24 that is formed in the body of the shank between a pair of lips 25 (Fig. 8), similar in principle to the lips 22. The purpose of the hump 23 is to prevent undue bending or yielding of the spring arm 16 away from the body of the shank. It is intended to keep the horn 20 substantially in the position shown. Were it not for the provision of the hump 23 there might be the possibility of breaking of the base 19 at the point 26 from the remainder of the needle surrounding the eye 13.

Breaking of the needle at the point 27 in the act of sewing is also prevented by the support which the heel 18 affords. The base 10 and horn 20 are relatively broad in the region of the eye 13, and by virtue of having bearing up against the heel 18 are held so firmly that there is little likelihood of breaking at the point 27 when sewing heavy goods.

The operation

is readily understood. Of necessity the spring arm is resilient at least to the degree of yielding sufficiently when a thread is introduced to the entrance between the channel from the rounded end 17 to the eye 13. The space between the body of the shank and the spring arm 16, base 19, horn 20 and point 21 is known as a channel through which the thread is slid in the act of threading the needle.

The mode of doing this would be to so adjust the fingers of the hand as to hold a portion of the thread under tension. This portion is then hooked around the rounded end 17 and slid down the long part of the channel, around the heel 18, over the hump 23, around the horn 20, and down around the point 21 until it occupies the eye 13. By vir-

tue of the constrictions to the channel that the hump 23 and point 21 present, it is necessary to adjust the thread from its originally straight-across position so that these configurations can be negotiated.

For example, it can be understood from Fig. 8 that the thread will be pulled toward one side of the needle in such a way that the components thereof are at rather sharp angles to each other. In this way, the thread is readily slipped around the point 21 until it enters the eye. The thread would be conveyed around the hump 23 in a similar manner.

Emphasis is to be laid on the hump 23 principally for its stabilizing function. It has been stated that the hump prevents outward bending of the spring arm 16 so that breaking at the point 26 in particular will be prevented. Lateral bending will be prevented also because the lodgment of the hump 23 in the recess 24 in position between the pair of lips 25 prevents any possibility of bending of the base of the spring arm at right angles to the plane of the paper.

In practice, the channel between the body of the shank 10 and the spring arm 16 as well as its associated base 19 and horn 20 will be made spacious enough to readily permit the sliding in of the thread. It is also a matter of mechanical perfection to so round the various corners and other parts of the needle that cutting of the thread will not be possible.

In conclusion, it is observed that a generous portion of the contour of the needle eye 13 is defined by the base 19. By virtue of this circumstance, it is essential to have the base of ample proportions so that breaking will not occur anywhere along the line of separation of the base from the shank 10. This function is aided in a large measure by the engagement of the hump 23 in the recess 24.

While the construction and arrangement of the improved needle is that of a generally preferred form, obviously modifications and changes may be made without departing from the spirit of the invention and the scope of the claims.

I claim:

1. A needle comprising a pointed shank having an eye and a recess, a resilient arm having a horn and a base connected with the shank and defining a part of the contour of the eye, and a hump on the horn loosely engaging the recess to limit the outward movement of the arm.

2. A needle comprising a pointed shank having an eye and a recess, a resilient arm having a base connected with the shank and a horn having a point confronting a part of the shank, said horn and shank defining a part of the contour of the eye and defining with the arm a channel for the passage of thread, a hump on the horn loosely engaging the recess, and a pair of lips on the shank

guarding and receiving the point therebetween.

3. A needle comprising a pointed shank having part of an eye, a heel in a medial line with the point, a resilient arm connected with the shank, a base comprising part of the arm at which the arm is connected with the shank, and a horn extending from the base beneath the heel and in the direction of and beyond the longitudinal center of the shank, said base and horn being formed to complete the eye.
